UNITED STATES PATENT OFFICE

STELLA JOSEPH, OF LOS ANGELES, CALIFORNIA

CALENDAR DEVICE

Application filed December 28, 1929. Serial No. 417,049.

My invention relates to calendars, diaries, and other devices in which a large number of dates, or blanks in connection with dates, or chronological, numerical, alphabetical materials are arranged in such manner as to be readily accessible at all times.

The objects of this invention are: first, to provide a device of this class whereby a large number of dates, calendar blanks, and the like, may be contained in a compact space, and whereby a portion or small group of such dates, blanks, or the like, may be temporarily segregated from the rest so that anyone of the group may be used or readily scrutinized; second, to provide a device of this class in the form of a calendar or diary which will contain data memoranda or calendar blanks for every day in the year, and in which several succeeding days are grouped together and designated by appropriate names as the past, present and future, such as "yesterday", "today", "to-morrow", on the succeeding day, so that the day and date of the past, present and future may be readily determined, as well as any notation, made on or for such days, observed; third, to provide a compact device having a many sided rotor on which is mounted a tape or other device in such manner that a portion thereof is exposed at each side and in which the greater portion of the tape or other device is wound on the inside of the rotor in such a manner that any portion of the tape may be readily exposed and the formerly exposed portion drawn inwardly so that only a small portion of the tape or other device is exposed at one time, the rotor being readily rotatable so that any one of the sides of the rotor may be turned toward the front for exposing the corresponding portion of the tape, or the like; fourth, to provide a device of this class whereby any portion of the calendar, or tape, or other recording member of the device, may be readily brought into view by the simple rotation of a knob, and whereby the rotor upon which the several portions of the calendar, tape, or other recording member, is brought into view, may be readily rotated by another knob independently of the former, so that any portion exposed on the rotor may be

quickly brought into view for viewing past, present, and future dates, data, and notations and for making future notations; fifth, to provide a device of this class for preserving past data and notations and for preserving the same in concealed form; sixth, to provide a device of this class from which the old and used up calendar, tape, or other recording member may be readily removed and a new one easily substituted; seventh, to provide a device of this class having interchangeable index or other tabs; eighth, to provide a novelly constructed multi-sided casing for housing the calendar, tape, or other recording member, and for exposing portions thereof at all of said sides; ninth, to provide novel means for mounting a fresh roll of calendar blanks, or other data, or tape, in a casing in and on which portions of the former are exposed; tenth, to provide a novel arrangement of rollers upon one of which the tape, or other member is wound while the other is unwound, the arrangement of rollers being such as to take up the greatest available space within the rotor or other member on which the tape is exposed so that the greatest possible roll of tape may be used; eleventh, to provide novel yieldable roller means adapted to engage the exterior surfaces of the rolls of tape to prevent the same from unrolling too freely; twelfth, to provide a device of this class in which a portion of the calendar blank or other tape is so exposed so as to provide a convenient writing surface thereon; thirteenth, to provide as a whole a novelly constructed device of this class; and, fourteenth, to provide a device of this class which is simple and economical of construction, proportionate to its functions, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters

of reference thereon which form a part of this application in which:

Figure 1 is a partial front and partial sectional view of my device in one form of construction; Fig. 2 is a fragmentary side elevational view thereof showing certain parts and portions broken away and in section for showing the means for winding and unwinding the tape; Fig. 3 is an enlarged fragmentary sectional view thereof taken at 3—3 of Fig. 2; Fig. 4 is an enlarged transverse sectional view thereof taken at 4—4 of Fig. 3; Fig. 5 is a fragmentary side elevational view of my device taken from the opposite side thereof and also showing certain parts and portions broken away and in section to facilitate the illustration; Fig. 6 is a perspective view of my device in its preferred form; Fig. 7 is a transverse sectional view thereof taken at 7—7 of Fig. 1; Fig. 8 is a fragmentary perspective view of a removable plate for securing the rollers to the inner casing or rotor; Fig. 9 is a sectional view thereof taken at 9—9 of Fig. 8; Fig. 10 is a fragmentary side view of the roller upon which the roll of tape or calendar, or the like, is initially mounted; Figs. 11 and 12 are, respectively, end views of the opposite end of said roller; Fig. 13 is a side view of the other roller upon which the tape or the like is wound; Figs. 14 and 15 are, respectively, end views from the opposite end of the latter roller; Fig. 16 is a side view of a key for holding the end of the tape upon the latter roller; Figs. 17 and 18 are, respectively, end views from the opposite ends of the key; Fig. 19 is a side view of the yieldable and resilient means for holding the tape wound on the roller; Fig. 20 is a developed view of exterior surface of the rotor showing the blank calendar tape in connection therewith; and Fig. 21 is a detail view of the inner rotor.

Like characters of reference refer to similar parts and portions throughout the views of the drawings.

My device, as shown in the drawings, is enclosed in a casing consisting of a casing member 1 and a cover 2, the latter being secured over one end of the former by screws 3. The casing is provided with a large interior 1a at its rear portion in which a rotor A is mounted and an inclined front and upper wall 1b which is inclined at a convenient angle for writing purposes. The rear wall 1c is circular so that the rotor A may revolve conveniently therein. Within the front portion and the bottom of the casing is a suitable weight 4 so that the casing cannot tilt backwardly readily. In the upper portion of the inclined wall is a rectangular opening 1d through which one face or side of the rotor A may project or be exposed.

The rotor is polygonal in cross section and, in this instance, is substantially triangular, the faces being slightly curved. The rotor

A consists of an outer rotor member 5 and an inner rotor member 6. The outer rotor member is provided with an end wall 5a and a side wall in triangular form extending to one side of the end wall. The triangular side wall, designated 5b, is provided with a large opening 5c at each side through which separate portions of the continuous calendar member, tape, or other recording member 7 may be seen, as shown best in the developed view in Fig. 20. The inner rotor member is also provided with an end wall 6a and triangular side walls 6b, but the side walls, in this instance, are all separate from each other, but secured at one edge to the inner side but inwardly from the end wall 6a. The side walls 6b, when the member 6 is positioned within the member 5, are spaced slightly inwardly from the inner sides of the side walls 5b of the rotor member 5, so that the tape 7, above referred to, may be extended through this space, designated B. At the vertices of the side walls of the member 6 are rollers 8, 9, 10 and 11 around which the tape is adapted to extend. The roll of tape, designated 12, is positioned within the inner rotor member and the tape 7 thereof extends first around the roller 8, then over the outer side of one of the side walls 6b, then around the roller 9, then around the next adjacent side wall of the member 6, then around the roller 10, then over the third side of the member 6, then around the roller 11, and then into the interior of the rotor. It will be noted that the lateral edges of the side walls 6b extend close to the sides of the rollers so that the tape may be drawn easily from one to the other without obstruction. The rollers are mounted in the end wall 6a of the member 6 and are removable therewith, the ends of the arbors of the rollers, opposite the end wall 6a, extending into ears 6e which extend inwardly from the edges of the walls 6b, as shown in Figs. 1 and 21.

At the outer sides of the end plates or walls 5a and 6a of the members 5 and 6 are annular flanges 5d and 6d which extend into annular recesses 1e and 2a in the end wall of the casing member 1 and in the cover 2, as shown in Figs. 1, 2, 5, 6 and 21. These annular flanges are coaxial with the axis of the rotor and rotatably support the same upon the casing above referred to.

At the axial portion of the end plate 5a is also provided a knob 13 for rotating the rotor. This knob extends through an opening 1f in the end wall of the casing member 1. On the hub 13a of the knob is a notched member 14 which is engaged by a spring actuated yieldable plunger 15 mounted within the recess 1e, as shown in Figs. 1 and 5. On the end wall 6a of the member 6 is also mounted a knob 16 which extends through an axial opening 2b in the cover member 2. The knob

16, however, is rotatably mounted with respect to the plate 6a and is provided on its top 16a with a gear 17 which meshes with a pair of pinions 18 and 19 which are loosely mounted on spindles 20 and 21 which are rotatably mounted in the end wall 6a. On the gears 18 and 19 are mounted pawls 22 which engage ratchets 23 and 24 fixed to the spindles 20 and 21. These ratchets, however, are so arranged that when the knob 16 is rotated in one direction, one of the spindles is rotated, and when rotated in the opposite direction, the other spindle is rotated.

To the edges of the side walls 6b of the member 6, opposite the end wall 6a, is removably secured a roller support 25 which is in the form of a plate removably clasped to the edges of the side walls 6b by any suitable means, such as shown in Figs. 8 and 9. On the inner side of this supporting plate are provided centers 25a and 25b on which are centered and mounted rollers 26 and 27, the former supporting the fresh roll of tape 12 and the latter receiving the used tape, that is, the latter rollers is adapted to unwind the tape from the former. The roller 26 is mounted at its opposite end on another center 28 carried at the inner end of the spindle 20. On the center 28 is also provided a key portion 29 which is adapted to extend into a corresponding slot, as shown in Figs. 10 and 12. The roller 27 is preferably fixed to the spindle 21. In the roller 27 is provided a longitudinally extending dovetail slot 27a in which is adapted to be fitted a correspondingly shaped key 30 which is provided at one end with a ring 30a which is adapted to be positioned at the end of the roller 27 and around the center 25b. This key is adapted to hold the end of the tape in order to wind the same thereon from the tape roll 12.

The tape is normally held taut on the rollers 26 and 27 and also the rollers 8, 9, 10 and 11 by yieldable rollers 31 and 32 which are rotatably mounted on frames 33 which are pivoted at one end within cylindrical members 34 in which are positioned coil springs 35, as shown in Figs. 7 and 19. One end of each coil spring is secured to the cylindrical casing and the other to the pivoted frame 33 so that the rollers 31 and 32 are normally forced against the roll of tape 12 and the tape wound on the roller 27.

The tape or dairy calendar, in this instance, consists of a continuous flexible tape, preferably of paper, which is equally divided into sections. Each section, designated 7a, is provided with a blank portion for recording engagements, data or general information. Each section is consecutively dated. Each section also bears the calendar of a month, but the consecutive sections are provided with calendars of different months so that the calendar of three months may be readily brought to view. For example, there

are three openings in the rotor member 5 which exposes three sections of the tape. These sections of the tape are provided with monthly calendars of December, January and February; the next following section is 70 provided with the monthly calendar of December, and so on in the same order to the end of the month when the month of December is dropped and the month of March added. The three openings in the rotor member 5 are 75 designated with the words "yesterday", "today" and "to-morrow". The opening designated "to-day" is normally turned to the front, that is, over the opening in the exterior casing, but the rotor may be either turned 80 backwardly or forwardly by the knob 13 so as to past or future calendar months may be viewed or so that past recorded data may be reviewed, or future engagements or notations for future reference made on the portion or section of the tape opposite the opening, designated "to-morrow".

At one side of each of the openings in the outer rotor member may be provided numbers 36a on a plate or index tab 36. These 90 numbers designate the hours of the day for which engagements are made or other data recorded. These index tabs, as well as the members 37 on which the days are imprinted may be removable, as shown, for changing the 95 indices.

When the roll 12 is used up and wound on the roller 27, the screws are removed which permits the removal of the plate 2. The rotor is then removed and the inner rotor member 100 removed from the outer rotor member. The plate 25 is then removed which permits the key 30 to be removed for removing the old roll of tape or the old calendar, or any other roll employed. A new roll is then placed 105 upon the roller 26, or a roll already mounted on the roller 26, is then placed in position with the free end secured in the roller 27 by the key 30. The plate 25 is then replaced and snapped into position. The other members 110 are then reassembled in the reverse order above outlined.

Though I have shown and described a particular construction, combination and arrangement of parts and portions, and a certain application of my invention, I do not wish to be limited to this particular construction, combination, and arrangement, nor to the particular application, but desire to include in the scope of my invention the construction, combination and arrangement, substantially as set forth in the appended claims.

Having thus described my invention, what I claim as new and desire to secure by Letters Patent is:

1. In a device of the class described, an enclosure having a plurality of sides with openings in said sides, a roll of tape mounted within the enclosure with different portions exposed to view through the different 130

openings, means for varying the position of the tape, and a supporting means for rotatably supporting the enclosure.

2. In a device of the class described, an enclosure having a plurality of sides with openings in said sides, a roll of tape mounted within the enclosure with different portions exposed to view through the different openings, a roller within the enclosure upon which the same is wound from the roll, and means for rotatably supporting said enclosure.

3. In a device of the class described, an enclosure having a plurality of sides with openings in said sides, a roll of tape mounted within the enclosure with different portions exposed to view through the different openings, a roller within the enclosure upon which the same is wound from the roll, means for rotatably supporting said enclosure, and means for rotating said roll and said roller in opposite directions independently of the rotation of the enclosure on the supporting means.

4. In a device of the class described, a casing having an inclined front side with an opening therein, a rotor rotatably mounted within the casing and provided with a plurality of sides, the sides thereof registering with the opening in the casing, and a single tape shiftably mounted within the rotor with a portion extended over the several sides of the rotor.

5. In a device of the class described, a casing having an inclined front side with an opening therein, a rotor rotatably mounted within the casing and provided with a plurality of sides, the sides thereof registering with the opening in the casing, and a roll of tape mounted within the rotor adapted to be drawn around all sides of the rotor and back into the rotor.

6. In a device of the class described, a casing having an inclined front side with an opening therein, a rotor rotatably mounted within the casing and provided with a plurality of sides, the sides thereof registering with the opening in the casing, and a roll of tape mounted within the rotor adapted to be drawn around all sides of the rotor and back into the rotor, said rotor having an inner wall around which the tape is drawn and an outer wall having openings therein through which data on the tape may be seen and other data recorded thereon.

7. In a device of the class described, a casing having an inclined front side with an opening therein, a rotor rotatably mounted within the casing and provided with a plurality of sides, the sides thereof registering with the opening in the casing, and a roll of tape mounted within the rotor adapted to be drawn around all sides of the rotor and back into the rotor, said rotor having an inner wall around which the tape is drawn and an outer

wall having openings therein through which data on the tape may be seen and other data recorded thereon, the sides of the rotor when registering with the opening in the casing being substantially at the same inclination as the upper side of the casing.

8. In a device of the class described, a casing having an opening in its upper side, a rotor mounted therein and projecting through the opening, and a tape shiftably mounted on the rotor, said rotor being adapted to be rotated for turning various portions of the tape toward and opposite the opening in the casing.

9. In a device of the class described, a casing having an opening, a rotor mounted within the casing and provided with a plurality of sides, and a tape mounted within the rotor and adapted to be drawn over the sides of the rotor and shiftable thereon, the sides of the rotor being separately registerable with the opening in the casing for viewing the data of the tape at the different sides of the rotor and for recording data at the different sides thereof.

10. In a device of the class described, an enclosure having a multiplicity of faces designating past, present and future time, and a calendar tape shiftably mounted on the enclosure and adapted to be positioned variously with respect to the time designations.

11. In a device of the class described, a supporting means, a rotor rotatably mounted thereon, said rotor comprising an outer rotor member having an end wall and a side wall secured thereto and provided with a plurality of sides having openings therein, and an inner rotor member having an end wall and side wall, the side wall fitting within and spaced from the side walls of the first rotor member, roller supporting means within the inner rotor member, a roll of tape mounted thereon and extending between the adjacent edges of two adjacent sides of the inner rotor member and around all sides thereof and back into the inner rotor member, and a roller within the inner rotor member adapted to unwind the tape from the roll.

12. In a device of the class described, a supporting means, a rotor rotatably mounted thereon, said rotor comprising an outer rotor member having an end wall and a side wall secured thereto and provided with a plurality of sides having openings therein, and an inner rotor member having an end wall and side wall, the side wall fitting within and spaced from the side walls of the first rotor member, roller supporting means within the inner rotor member, a roll of tape mounted thereon and extending between the adjacent edges of two adjacent sides of the inner rotor member and around all sides thereof and back into the inner rotor member, a roller within the inner rotor member adapted to unwind the tape from the roll, means for rotating said

roll and said roller in opposite directions, and other means separately rotating the rotor.

13. In a device of the class described, an enclosure, a pair of rollers rotatably mounted therein in spaced parallel relation, a roll of tape mounted on one of the rollers and adapted to extend around the enclosure and adapted to be wound up on the other roller, the tape when wound on the first roller substantially engaging one side of the interior of the enclosure, and when wound upon the other roller substantially engaging a substantially opposite side of the interior of the enclosure, said rollers being also positioned a minimum distance apart.

14. In a device of the class described, a rotatable enclosure having a plurality of sides forming rigid writing surfaces, a tape mounted therein and extended with a portion thereof over the writing surfaces.

15. In a device of the class described, a casing having an opening, a rotor mounted within the casing and provided with a plurality of sides adapted to register with the opening in the casing, and a single tape shiftably mounted on the rotor with a portion of the tape extended over the several sides of the rotor and accessible through the opening in the casing for writing upon the tape at the several sides of the rotor.

In testimony whereof, I have hereunto set my hand, at Los Angeles, California, this 13th day of December, 1929.
